FRANK J. VLCKEK, OF CLEVELAND, OHIO, ASSIGNOR TO THE VLCKEK TOOL COMPANY,
OF CLEVELAND, OHIO, A CORPORATION OF OHIO

DROP HAMMER

Application filed April 24, 1931. Serial No. 532,395.

My invention relates to drop hammers, and particularly to means for elevating the hammer heads of drop hammers, and the principal object of my invention is to provide new and improved means of this type. This application is a continuation in part of my co-pending application Serial Number 386,467 filed August 16, 1929. In the drawings accompanying this specification and forming a part of this application I have shown, for purposes of illustration, one form which my invention may assume, and in these drawings:

Figure 1 is a front elevation of a drop hammer embodying my invention.

Figure 2 is a section on the line 2—2 of Figure 1,

Figure 3 is a section on the line 3—3 of Figure 1,

Figure 4 is a view in elevation of a board employed in the embodiment of my invention herein shown, while

Figure 5 is an enlarged view of a fragment of Figure 2, showing in detail the contours of the rollers and of the board.

I have shown herein a hammer 11 comprising a base 12 on which is mounted an anvil 13; from this base 12 rise side bars 14 providing guides 15 in which the hammer head 16 is reciprocable and united at their upper ends by a top plate 17 to which is suitably secured the base plate 18 of the hammer head operating mechanism 19.

The hammer head operating mechanism 19 comprises a pair of shafts 20 and 21 mounted in eccentric bearings 22 and 23 themselves mounted in bearing apertures 24 and 25 formed in two brackets 26 secured to and rising from the hammer head operating means base plate 18. The shaft 20 is provided at its ends with pulleys 27 adapted to receive belts (not shown) by which the shaft 20 may be driven. The two eccentric bearings for the shaft 20 are connected by a combined crank and housing 28 by means of which the bearings 22 may be rotated, and held in position, thus to adjust the position of the shaft 20 to take up wear, and to hold the shaft 20 in adjusted position, while the two eccentric bearings 23 of the shaft 21 are

connected by a similar combined crank and housing 29, and in addition carry at one end a depending arm 30 having at its lower end a follower 31 cooperating with a cam 32 carried by a control shaft 33, whereby oscillation of the control shaft 33 will operate through the cam 32 and follower 31 to correspondingly oscillate the eccentric bearings 23 of the shaft 21, thus alternately to advance and retract the shaft 21.

Mounted on the shafts 20 and 21 are a pair of rolls 34 and 35 each provided on its periphery with a pair of V-channels 36 in which are positioned tail-piece means comprising a pair of wooden boards 37 each truncated-V-convex on each side, to be embraced within the channels 36 of the rolls 34 and 35 when the roll 35 is approached toward the roll 34, and each flattened at its lower end at 38, to be received in a suitable recess 39 in the hammer head 16, and locked to the hammer head 16 by means of suitable wedges 40.

From the above it of course will be understood that when the roll 35 is approached toward the roll 34 the boards 37 will be gripped, thus raising the compressible fibrous boards 37 and the hammer head 16, and that when the roll 35 is subsequently retracted, as occurs when the hammer head 16 has been suitably elevated, the rolls 34 and 35 will release the boards 37, thus to permit the hammer head 16 to drop, strike its blow, and be ready for a subsequent elevation; also it will be obvious that with the construction herein shown the boards 37 are embraced within the channels 36 in the rollers 34 and 35, thus to produce a greater surface pressure between the boards and the rolls with the same pressure on the rolls, and simultaneously to support the boards against disruption, and retard deterioration of the boards.

It will be noted, however, that the truncation of the boards 37 provides a clearance 41 at the apex of the convexity, into which the boards may flow, under the action of the compression exerted by the rolls 34 and 35; in actual practice this seems to be advantageous, both as facilitating the grip of the rolls on the board, and as a result, the speed with which the hammer may be operated, and also

as increasing the permissible life of the board.

Under these circumstances those skilled in the art will realize that the embodiment of my invention herein shown and described accomplishes at least the principal object of my invention; at the same time those skilled in the art will realize that the particular embodiment of my invention herein shown and described may be variously changed and modified without departing from the spirit of my invention, or sacrificing the advantages thereof, and particularly that I may vary the contour of the boards and channels, the number of boards and channels, unite the boards into a single board, separate the rolls into individual rolls, embrace the board or boards otherwise than as herein shown, and employ my invention in other types of drop hammers, and accordingly it will be understood that the disclosure herein is illustrative only, and that my invention is not limited thereto.

I claim:

1. Actuating mechanism, as for actuating a drop-hammer hammer-head, including: a pair of cooperating roller means, and a rigid board of fibrous woody material, disposed therebetween and resiliently compressible under pressure; said roller means being forcibly engageable with said board, said board on the side toward at least one of said roller means being convex, and said roller means being cooperatively concave, such convexity and concavity being of such sharp contour that said roller means embraces laterally to hold said board against slipping and edgewise splitting.

2. Actuating mechanism, as for actuating a drop-hammer hammer-head, including: a pair of cooperating roller means, and a rigid board of fibrous woody material, disposed therebetween and resiliently compressible under pressure; said roller means being forcibly engageable with said board, said board on the side toward at least one of said roller means being substantially V-convex, with the angle of the convexity being not materially greater than ninety degrees, and said roller means being cooperatively concave, to hold said board against splitting and slipping.

3. Actuating mechanism, as for actuating a drop-hammer hammer-head, including: a pair of cooperating roller means, and a rigid board of fibrous woody material, disposed therebetween and resiliently compressible under pressure; said roller means being forcibly engageable with said board, said board being substantially rhomboidal in cross-section, and diagonally disposed, and said roller means being cooperatively concave, to hold said board against splitting and slipping.

4. Actuating mechanism, as for actuating a drop-hammer hammer-head, including: cooperating roller means, and a rigid board disposed therebetween; said board being of

fibrous woody material, and resiliently compressible under pressure, and said roller means being forcibly engageable with said board, substantially encircling said board about the cross-sectional periphery thereof, and engaging at least partly along inclined lines of contact, wedging said board, to hold said board against slipping and splitting. 70

5. Actuating mechanism, as for actuating a drop-hammer hammer-head, including: a pair of cooperating roller means, and a rigid board of fibrous woody material, disposed therebetween and resiliently compressible under pressure; said roller means being forcibly engageable with said board, said board on the side toward at least one of said roller means being convex, and said roller means being cooperatively concave, such convexity and concavity being of such sharp contour that said roller means embraces laterally to hold said board against slipping and edgewise splitting, and said roller means and said board being so contoured that said board and said roller means do not contact at the apex of said convexity. 80

6. Actuating mechanism, as for actuating a drop-hammer hammer-head, including: a pair of cooperating roller means, and a rigid board of fibrous woody material, disposed therebetween and resiliently compressible under pressure; said roller means being forcibly engageable with said board, said board on the side toward at least one of said roller means being substantially V-convex, with the angle of the convexity being not materially greater than ninety degrees, and said roller means being cooperatively concave, to hold said board against splitting and slipping, said board however being truncated, and spaced from said roller means, at the apex of its convexity. 100

7. Actuating mechanism, as for actuating a drop-hammer hammer-head, including: a pair of cooperating roller means, and a rigid board of fibrous woody material, disposed therebetween and resiliently compressible under pressure; said roller means being forcibly engageable with said board, said board being substantially rhomboidal in cross-section, and diagonally disposed, and said roller means being cooperatively concave, to hold said board against splitting and slipping, said board however being truncated, and spaced from said roller means, on all diagonals of said board. 110

8. Actuating mechanism, as for actuating a drop-hammer hammer-head, including: a pair of cooperating roller means, and a rigid board of fibrous woody material, disposed therebetween and resiliently compressible under pressure; said roller means being forcibly engageable with said board, said board on the side toward at least one of said roller means being convex, and said roller means being cooperatively concave, such convexity 120

and concavity being of such contour that said roller means embraces laterally to hold said board against slipping and edgewise splitting, and said roller means and said board being so contoured that said board and said roller means do not contact at the apex of said convexity.

9. Actuating mechanism, as for actuating a drop-hammer hammer-head, including: a pair of cooperating roller means, and a rigid board of fibrous woody material, disposed therebetween and resiliently compressible under pressure; said roller means being forcibly engageable with said board, said board on the side toward at least one of said roller means being substantially V-convex, and said roller means being cooperatively concave, to hold said board against splitting and slipping, said board however being truncated, and spaced from said roller means, at the apex of its convexity.

In testimony whereof I hereunto affix my signature.

FRANK J. VLCHEK.
